SIGNAL CONSTRUCTION

Paul N. Becka, 1308 Bunts Road, Lakewood, Ohio
Filed Apr. 4, 1960, Ser. No. 19,963
9 Claims. (Cl. 340—105)

The invention relates in general to signals and more particularly to pedestrian control signals which are easily assembled and disassembled with consequent ease in servicing and repairing the same.

Pedestrian control signals which are in use at the present time are generally mounted on a pole or post at an intersection with the back of the housing which contains the signal components butting up against the post. The electrical circuit components which energize and de-energize the signal lamps are fixedly secured within the housing. Consequently when the signal needs repair, it is difficult, if not impossible, to get at the electrical circuit components without removing the entire signal from its mounting place. If it is possible to gain entrance to the inside of the housing to get at the electrical circuit components, it is generally awkward and difficult to work on the same because of the limited amount of space in which there is to mount the components. It is also dangerous from the standpoint that there is generally no way to disconnect the electrical components from the source of power which is used to energize the signal.

It is therefore an object of the present invention to provide a control signal and more particularly a pedestrian control signal which is easily serviced and repaired without having to remove the entire signal from its mounting place.

Another object of the invention is to provide a pedestrian control signal which may be opened and entered from the front.

Another object of the invention is to provide a pedestrian control signal wherein the lamps and electrical circuit components are mounted upon a removable tray which may be removed from the signal in the event they come into disrepair and may be readily repaired.

Another object of the invention is to provide a pedestrian control signal which has a source of electrical energy cooperating therewith to energize the same, with a new and novel switch means for alternatively connecting and disconnecting the source of electrical energy.

Another object of the invention is to provide a pedestrian control signal which includes a housing and a hood, each have complementary mating flanges, with a means for securing a side of each of the flanges together to provide for a lost motion swinging movement between the two to provide entrance to the housing.

Another object of the invention is to provide a pedestrian control signal including a removable tray which carries lamps and the electrical circuit components for operating the lamps, with switch means for alternatively connecting and disconnecting a source of electrical energy and the electrical circuit components which switch means include a fixed part mounted by the housing and a movable part mounted by said removable tray and including a handle for moving the movable part.

Another object of the invention is to provide a pedestrian control signal having a translucent or transparent panel with instructions thereon with a new and novel means for holding the panel in place.

Another object of the invention is to provide a pedestrian control signal with an enclosure member to house lamp means with opposite ends of the enclosure being closed by a transparent or translucent panel and a tray or panel member which carries the lamp means on one side thereof and electrical circuit components on the other.

Other objects and a fuller understanding of the inven-

2

tion may be had by referring to the following description and claims, taken in conjunction with the accompanying drawings, in which:

5 FIGURE 1 is an isometric view of the signal of the present invention as mounted on a supporting post;

FIGURE 2 is an exploded isometric view of the signal shown in FIGURE 1;

FIGURE 3 is a side elevational view in section of the signal shown in FIGURE 1;

10 FIGURE 4 is a fragmentary view of the switch means shown in FIGURE 3;

FIGURE 5 taken along the line 5—5 of FIGURE 4;

FIGURE 6 is a view of the back side of the removable tray shown in FIGURE 2;

15 FIGURE 7 is an exploded isometric view of another signal constructed under the teachings of the present invention;

FIGURE 8 is an isometric view of the parts shown in FIGURE 7 with the parts in assembled condition;

20 FIGURE 9 is an exploded isometric view of one of the exploded parts shown in FIGURE 7;

FIGURE 10 is a side elevational view in section of the signal shown in FIGURE 8;

25 FIGURE 11 is a view taken generally along the line 11—11 of FIGURE 10;

FIGURE 12 is a view taken generally along the line 12—12 of FIGURE 10; and

FIGURE 13 is a view taken generally along the line 13—13 of FIGURE 10.

30 The control signal of the present invention has been indicated generally by the reference numeral 10 and in FIGURE 1 has been shown as mounted to a supporting post 11. The signal includes a housing 12 which has top, bottom, back, and first and second side walls indicated by the reference numerals 13 through 17, respectively.

35 The housing may also be referred to as having a back wall and four side walls. The top and bottom walls and the first and second side walls of the housing terminate at their ends opposite the back wall 15 to form an open front face on the housing which is generally defined by a flange 20 which extends around this open front face. The signal 10 also includes a hood 23 which comprises an annular frame 24 which has a flange 27 which is complementary to the housing flange 20. Integrally formed

40 with the annular frame and extending therefrom on a side opposite the flange 27 are first and second side walls 29 and 30, respectively, and a top wall 28. Mounted in the annular frame 24 is a transparent closure member 33; for example, constructed of glass or plastic material. When

45 the signal 10 is in use, the hood 23 and the housing 12 are secured together as shown in FIGURES 1 and 3 by bolts 37 which extend through mating holes 36 which are provided in the respective flanges. A sealing member 40 is disposed between the flanges 20 and 27 to provide a 50 tight seal between the hood and the housing. To provide a lost motion swinging movement between the hood and the housing in the event it is desired to expose the interior of the housing, first and second rings 42 and 43, respectively, are provided which extend through the bottom sides of the flanges 20 and 27. This permits the housing to be opened from the front while still preventing complete separation of the hood and housing whereby the hood will never become lost from the control signal. This loose connection which is provided by the use of the

55 rings 42 and 43, respectively, permits the flanges to be adjusted so that the holes 36 match up and so that the bolts 37 may be inserted therethrough to secure the hood in place as shown in FIGURES 1 and 3 for use during operation of the signal.

60 As best seen in FIGURE 2, first and second brackets 46 and 47 are respectively mounted to the top and bottom walls 13 and 14, respectively, of the housing 12.

65

70

A removable tray or panel 50 having substantially the same dimensions as the inner dimensions of the housing is mounted within the housing by the brackets 46 and 47, respectively. The tray is secured to the brackets by means of screw members 48. As will be noted in FIGURE 3, the brackets 46 and 47 are spaced from the open face of the housing a predetermined distance which is substantially the same dimension as the depth of the removable tray 50. Handles 53 are provided on the tray 50 to facilitate moving of the same. The removable tray 50 is provided with first and second side portions 51 and 52, respectively, and the first side portion mounts a gaseous discharge lamp 55 which is in the form of a continuous luminous tube. This continuous tube, as will be readily recognized, could be a plurality of tubes rather than a single continuous one. The lamp which is carried by the first side portion of the tray, as will be noted, is formed into the words, "DON'T" and "WALK." The words, of course, could be different and could convey the same or different messages. The second side portion 52 mounts electrical circuit components which have been referred to generally by the reference numeral 58. The electrical circuit components and the lamps which are carried by the removable tray might be, for the sake of example, the same as those disclosed in my co-pending United States patent application, Serial No. 653,705, filed April 18, 1957. The electrical circuit components 58 which are carried by the second side of the removable tray are energized and de-energized by an electrical energy source which comes from a traffic controller separate from the signal here shown. This source of electrical energy has been shown in the accompanying drawings as entering the housing by way of three electrical conductors 59, 60, and 61, respectively (FIGURES 3 and 4). Interposed between the electrical circuit components 58 and the electrical conductors which bring in the source of electrical energy is switch means indicated generally by the reference character 62 and best shown in FIGURES 4, 5, and 6. The switch means 62 includes generally a fixed part 64 and a movable part 65. The fixed part 64 includes an insulated mounting strip 66 secured to the second side wall 17 of the housing 12 by members 67. Mounted to and extending from the strip 66 are three fixed contacts 70. The electrical conductors 59, 60, and 61 are each electrically secured to a fixed contact 70 as at 71. The movable part 65 of the switch means 62 includes a bracket 73 secured to the second side of the removable tray 50. Fixedly secured to the bracket 73 is an insulated mounting support 74 from which guide members 75 laterally extend. Three movable contacts 76 which are adapted to engage the fixed contacts 70 are mounted on a slidable member 77 which in turn is guided in its movement by the guide members 75 extending through elongated slots 78 in member 77. Secured to the slidable member 77 is a handle 80 which extends through the removable tray to the first side thereof where it may be readily reached upon gaining access to the housing through the open face. Each of the three movable contacts 76 are electrically connected to electrical conductors 82, 83, and 84, respectively, which in turn are connected to the electrical circuit components 58 which are mounted upon the second side of the removable tray 50. FIGURES 4 and 5 show the switch means 62 in the connected position and FIGURE 4 shows the switch means in the disconnected position. In the position shown in FIGURE 3, the panel 50 defines a first compartment 89 within which the gaseous discharge tube resides and a second compartment 90 within which the circuit components reside. The gaseous discharge tube 55 which has been shown is supplied with electrical energy at its end portions by means of terminals 85 and 86, respectively, and at its intermediate portion by terminal 87.

In operation, if it be desired to gain access to the interior of the signal as shown in FIGURE 1, it is

necessary to remove the bolts 37 which extend through the holes 36 in the flanges 20 and 27. When this has been done, the hood is swung into the position shown in FIGURE 2 whereat the rings 42 and 43 keep the housing and hood from becoming completely separated from each other. The switch means 62 is then disconnected by grasping the handle 80 and pulling outwardly from the position shown in FIGURE 4 to that which is shown in FIGURE 3. The source of electrical energy is now disconnected from the electrical circuit components which are carried by the removable panel or tray. The removable panel can then be easily removed from the housing by unscrewing the screw members 48 which extend into the brackets 46 and 47. The removable panel which carries the lamps and the electrical circuit components may then be carried by the handles 53 and removed and may be immediately replaced by another panel. It will be noted that the handles 53 extend out beyond the extent of the discharge tube or lamp means whereby the panel may be laid on its first side portion while being worked on without damage to the tube. The defective panel may then be removed to a repair shop where it can again be put in working condition without shutting down the control signal. In the event the repairs are not extensive, the defective panel may be removed from the housing and worked on immediately and put back into service with little danger from electrical energy because of the inability to disconnect the signal from the source of electrical power. The panel or tray may also be conveniently manipulated and can be easily removed from the housing and as a result work upon the same is rendered quite simple. It is also unnecessary as will be observed, to completely dismantle the signal from the support post to which it is attached, which is in most instances, quite a job. It will be noted that entrance to the housing is gained from the front rather than from the rear and access to the device is quite simple as compared to other devices. The use of the ring members 42 and 43 insures that the hood and the housing do not become separated and also provides for a loose connection so that the respective flanges may be aligned and the bolts inserted through the holes to secure the hood and housing together.

FIGURES 7 through 13 show the modified form of the pedestrian control signal which includes in combination a housing 100 having a back wall 101, four side walls 102 through 105, respectively, and an open front face. A hood 108 is secured to the housing 100 by way of screws 109, and the hood extends around three sides of the open front face. The hood serves to enable pedestrians to observe the signal more easily. Wall means 111 serve to define a flange which is carried on the side walls and extends completely around the inner surface of the housing. As will be noted, the flange is spaced from the open front face of the housing a predetermined distance.

A tray or panel member 114 is provided which has substantially the same shape as the open front face of the housing and is also provided with first and second side portions 116 and 117, respectively. Lamp means 119 are carried on the first side of the tray 116 and in this embodiment, the lamp means include first, second, and third continuous gaseous tubes 121, 122, and 123, respectively. The tubes 121 and 122 are preferably red in nature when illuminated, and the gaseous tube 123 is preferably green in color. Electrical circuit components 125 are carried on the second side 117 of the tray and serve to aid in illuminating the gaseous discharge tubes carried on the first side of the tray. These electrical circuit components are similar to those described in the signal of FIGURES 1 through 6. An enclosure member 127 is provided for housing the lamp means referred to above and the enclosure member comprises four side walls 129 through 132, which give the enclosure member substantially the same shape as the open

front face of the housing and a depth approximately the same as the above-referred to predetermined distance. Before assembly, the enclosure member has an open front and back. A wall member 134 serves to divide the enclosure member into first and second chambers 135 and 136, respectively. The open front of the first and second chambers 135 and 136 are closed by transparent or translucent glass members 139 and 140, respectively. The glass member 139 has black paint applied on the inner surface thereof in such manner as to spell out the word "DON'T"; and in a like manner, the word "WALK" is spelled out on the second glass member 140. A sealing member 142 (FIGURES 10, 11, and 13) extends completely around each of the glass members 139 and 140 and lies between the glass members and a flange 144 on the enclosure member 127. The sealing member 142 is squeezed between the glass member and the flange 144 by means of a plurality of springs 146. The construction and operation of each one of the spring members 146 may be best understood by referring to FIGURE 13. Each of the springs 146 is constructed of flat spring material having a first end portion 148 lying in generally flat engagement with the glass member. A toe portion forms an integral part of the spring and overhangs a side of the glass member to prevent movement of the spring member in one lateral direction, indicated by the arrow 151. The direction of the force tending to squeeze the sealing member 142 between the glass member and the flange 144 has been indicated by the arrow 152. The spring has a second end portion 154 which is secured to and extends from the first end portion 148. The extreme end of the second end portion 154 engages an abutment 155 for a purpose which will be described hereinafter. The straight line distance between the abutment 155 and the point of connection 156 between the first and second end portions of the spring is less than the length of the second end portion. As a result, in order to assemble the spring member into the full line position indicated in FIGURE 13, it is necessary to first place the spring in the dotted line position and move it into the full line position by pushing it in a direction opposite to the arrow 151. It may thus be said that the second end portion of the spring in the assembled condition is bowed in another lateral direction which is opposite to the lateral direction indicated by arrow 151. It will thus be seen that any force exerted on the glass members from outside the enclosure only tends to urge the spring members more strongly in said another lateral direction.

The back of the enclosure member 127 is closed by means of the tray or panel member 114 which is secured in place by means of screws 158. With the tray in place, as described, the gaseous discharge tube 121 resides in the first chamber 135 whereas gaseous discharge tubes 122 and 123 reside in the second chamber 136. Handles 159 and 160 are connected to the enclosure member and serve as a convenient means for placing the enclosure member with the attached tray into and out of the housing. The enclosure member is securely held in position in the housing by means of bolts 161 which extend through U-shaped slot 162 in the end of a bar member 163 which is fixedly connected to the enclosure member.

In order to supply electrical energy to the electrical circuit components and the lamp means, a switch indicated generally by the reference numeral 166 has been provided. The switch includes a first switch part 168 fixedly mounted on the side wall 102 of the housing 100 a distance from the open front face which is greater than the above-referred to predetermined distance. The switch also includes a second switch part 170 which is fixedly secured by means of bolts 171 to the second side of the tray 114. The second switch part 170, therefore, moves with the tray or panel member.

It will thus be seen that when the enclosure member to which the panel member 114 is attached, is removed from the housing by using the handles 159, and 160,

the first and second switch parts 168 and 170, respectively, are separated. This disconnects the electrical circuit components and the lamp means from the external source of electrical energy which is supplied to the first switch part 168 in a manner similar to that shown in the device of FIGURES 1 through 8. FIGURE 12 shows the first and second switch parts in contacting engagement with each other when the enclosure member is in place in the housing and resting against or supported by the flange 111. It is with this construction that the new and novel means for housing the gaseous discharge tubes in the enclosure member is provided along with the convenient means of disrupting the supply of electrical energy when the panel member and enclosure member are removed from the housing. It will also be appreciated that the spring means provided for holding the translucent or transparent panels in position provides a very novel construction. It might also be pointed out that the arrangement of the electrical circuit components is such that tubes 121 and 122 are energized at the same time, thus illuminating the words, "DON'T WALK" in red and tube 123 is energized by itself thus illuminating the word, "WALK" in green.

This application is a continuation-in-part of my application, Serial No. 663,142, filed June 3, 1957, for Signal Construction.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

35 What is claimed is:

1. A pedestrian control signal including a housing having top, bottom, back and first and second side walls, said housing having an open front face, a flange extending around said open front face, an annular frame having a flange complementary to said flange of said housing, a top wall and first and second side walls on said frame, a transparent closure carried by said annular frame, said frame and housing flanges being secured together by bolts extending through the same and with a sealing member therebetween, first and second ring members extending through said frame and housing flanges to permit swinging movement of said frame and housing relative to each other without complete separation of same to expose said open front face of said housing, brackets secured to the inside walls of said housing a spaced distance from said open face, a removable tray mounted in said housing by said brackets and having first and second side portions, said first side portion mounting a luminous tube, handles on said tray extending beyond the extent of said luminous tube for protection of same, said second side portion mounting electrical circuit components for effecting energization of said luminous tube, switch means for alternatively connecting and disconnecting said electrical circuit components to an electrical power source, said switch means including a fixed part secured to one of said housing walls, a movable part movable into and out of engagement with said fixed part, a lost motion connection between said movable part and said removable tray for actuation of said switch means as said tray is inserted and removed from said housing, and an insulated handle member operably connected to said movable part and extending from said first side portion of said removable tray for moving said movable part into and out of engagement with said fixed part to actuate said switch means independently of movement of said tray.

2. A pedestrian traffic signal comprising, a housing having a back wall and four side walls and an open face, bracket supports carried on said side walls and spaced from said open face a predetermined distance, a tray having the same size and shape as said housing and a

depth approximately said predetermined distance and adapted to abut said bracket supports, first and second sides on said tray, gaseous discharge lamp means carried on said first side of said tray adapted to face the open face of the housing, electrical circuit components carried on said second side of said tray for effecting energization of said lamp means, a disconnect switch comprising first and second parts, said first part being mounted on a side wall of said housing at a distance from said open face greater than said predetermined distance, means for supplying energization to said first part, lost motion means for mounting said second part on said second side of said tray, contact means on said second part movable into engagement with contacts on said first part with said tray in engagement with said bracket supports, and a plunger connected to said movable contact means extending through said tray to said first side thereof, and means to fasten said tray to said bracket supports, whereby upon removal of said fastening means, said tray, lamp means and electrical components may be removed as a unit from said housing through said open face for servicing with consequent separation of said disconnect switch.

3. A pedestrian traffic signal comprising, a housing having a bottom wall and four side walls and an open face, bracket supports carried on said side walls and spaced from said open face a predetermined distance, a tray having the same size and shape as said housing and a depth approximately said predetermined distance and designed to complementarily rest upon said bracket supports, first and second sides on said tray, gaseous discharge lamp means carried on said first side of said tray, electrical circuit components carried on said second side of said tray for effecting energization of said lamp means, a disconnect switch comprising first and second parts, means for supplying energization to said first part, lost motion means for mounting said second part on said second side of said tray, movable contact means on said second part movable into engagement with contacts on said first part with said tray in engagement with said bracket supports, and a plunger connected to said movable contact means extending through said tray to said first side thereof, and means to fasten said tray onto said bracket supports, whereby upon removal of said fastening means said tray and lamp means and electrical components may be removed as a unit from said housing through said open face.

4. A signal comprising, a housing having a closed back wall and an open front face, an annular frame adapted to complementarily cooperate with said front face opening, a first flange around said front face opening on said housing, a second flange on said annular frame, cooperating holes in at least two sides of said first and second flanges for fastening bolts, and rings loosely connecting two sides of said first and second flanges for a lost motion hinge movement, whereby said rings permit alignment movement of said annular frame relative to said housing to align said holes to permit fastening bolts to be inserted therethrough.

5. A signal including a housing, wall means defining an opening into said housing, a panel having first and second side portions, lamp means carried by said first side portion of said panel, electrical circuit components for illuminating said lamp means carried by said second side portion of said panel, said panel being removable from said housing through said opening, means for securing said panel within said housing, an electrical energy source supplying energy to said electrical circuit components, switch means between said electrical energy source and said electrical circuit components, said switch comprising a fixed part mounted by said housing and a movable part, lost motion means mounting said movable part on said second side portion of said panel, and a handle operably connected to said movable part for moving same into and out of contact with said fixed part.

6. A signal including in combination a housing, wall

means defining a front opening into said housing, a panel having a first and second side portions, lamp means carried by said first side portion of said panel, electrical circuit components for illuminating said lamp means carried by said second side portion of said panel, handle means mounted on said first side portion of said panel and extending beyond the extent of said lamp means, means for removably securing said panel within said housing, said panel being removable from said housing through said front opening, hood means for closing said front opening of said housing, an electrical energy source supplying energy to said electrical circuit components, switch means between said electrical energy source and said electrical circuit components, said switch means comprising a fixed part mounted on said housing and a movable part, lost motion means mounting said movable part in said second side portion of said panel to be movable relative to said fixed switch part and said panel, and an insulated handle operably connected to said movable switch part and extending outwardly of said first side portion of said panel for moving said movable switch part into and out of contact with said fixed switch part.

7. A pedestrian control signal including a housing, wall means defining an opening into said housing, a panel having first and second side portions, lamp means carried by said first side portion of said panel, electrical circuit components for illuminating said lamp means and carried by said second side portion of said panel, said panel being removable from said housing through said opening, means for securing said panel within said housing, an external source of electrical energy supplying energy to said electrical circuit components, switch means between said electrical energy source and said electrical circuit components, said switch means comprising a first part fixedly mounted by said housing and a second part mounted by said second side portion of said panel and movable therewith, and handle means for alternately removing said panel from and placing said panel in said housing whereby said first and second switch parts are alternately disconnected and connected.

8. A pedestrian control signal including in combination a housing having a back wall, four side walls, and an open front face, wall means defining a flange carried on said side walls and spaced from said open front face a predetermined distance, a tray having substantially the same shape as said open front face, said tray having first and second side portions, lamp means carried on said first side portion of said tray and adapted to face the open face of said housing, electrical circuit components carried on said second side portion of said tray for effecting energization of said lamp means, and enclosure member for said lamp means comprising four side walls having substantially the same shape as said open front face and a depth approximately said predetermined distance and supported by said flange said enclosure member having an open front and back, said open front of said enclosure member being closed by a transparent member through which said lamp means are visible, said tray closing said open back of said enclosure member with said lamp means residing within said enclosure member, handle means on said enclosure member for removing and placing same in said housing, a switch for supplying electrical energy to said electrical circuit components and said lamp means and comprising first and second parts, said first switch part being fixedly mounted on a side wall of said housing at a distance from said open face greater than said predetermined distance, means for supplying electrical energy to said first switch part said second switch part being fixedly mounted on said second side portion of said tray and in contact with said first switch part with said enclosure member supported by said flange, fastening means to fasten said enclosure member to said housing with same supported by said flange whereby removal of said fastening means said handle means may be grasped and said enclosure member, tray, lamp means

and electrical components may be removed as a unit from said housing with the removal causing separation of said first and second switch parts and thus interrupting the supply of electrical energy to said electrical circuit components and lamp means.

9. A pedestrian control signal including in combination a housing having a back wall, side walls, and an open front face, a flange carried by said housing and spaced from said open front face a predetermined distance, a tray having substantially the same shape as said open front face, said tray having first and second side portions, lamp means carried on said first side portion of said tray and adapted to face the open face of said housing, electrical circuit components carried on said second side portion of said tray for effecting energization of said lamp means, an enclosure member for said lamp means comprising four side walls having substantially the same shape as said open front face and a depth approximately said predetermined distance and located at said flange, said enclosure member having an open front and back, said open front of said enclosure member being closed by a member through which said lamp means are visible, said tray closing said open back of said enclosure member with said lamp means residing within said enclosure member, handle means on said enclosure member for removing and placing same in said housing, a switch for supplying

electrical energy to said electrical circuit components and said lamp means and comprising first and second parts, said first switch part being fixedly mounted on a side wall of said housing at a distance from said open face greater than said predetermined distance, means for supplying electrical energy to said first switch part, said second switch part being fixedly mounted on said second side portion of said tray and in contact with said first switch part with said enclosure member supported by said flange, fastening means to fasten said enclosure member to said housing with same supported by said flange whereby upon removal of said fastening means said handle means may be grasped and said enclosure member, tray, lamp means and electrical components may be removed as a unit from said housing with the removal causing separation of said first and second switch parts and thus interrupting the supply of electrical energy to said electrical circuit components and lamp means.
